HYDRAULIC ACCUMULATOR

Richard W. Dinzl, Drexel Hill, Pa., assignor to
Baldwin-Southwark Corporation, Eddystone,
Pa., a corporation of Pennsylvania

Application January 11, 1932, Serial No. 536,005

5 Claims. (Cl. 103—222)

My invention relates to accumulators such as are employed with hydraulically operated machinery for storing or accumulating liquid, usually water, under a head which may be subsequently translated into pressure and delivered to such machinery when maximum demand exceeds the pumping capacity supplying such machinery or when for any reason the pumping capacity requires regulation to maintain the required demand.

One object of my invention is to provide an accumulator with simple and efficient means for varying the loading of the same.

A further object of my invention is to provide an accumulator having variable loading means with means whereby portions of such load may be readily displaced when it is desired to vary the pressure at which the liquid is delivered.

A further object of my invention is to provide an accumulator with detachable or displaceable loading means and associated mechanism whereby variations in the loading, and consequently in the delivered pressure may be controlled at a distance from the accumulator.

These and other objects of my invention will be readily apparent from the following description and from the accompanying drawings illustrating one embodiment of my invention, and in which:

Fig. 1 is an elevation of my improved accumulator.

Fig. 2 is a plan view of the same.

Fig. 3 is a vertical section taken on the line III—III, Fig. 2.

Fig. 4 is a sectional plan taken on the line IV—IV, Fig. 3, and

Figs. 5 and 6 are fragmentary views illustrating details of my invention.

The accumulator proper is of the usual type comprising a vertical cylinder 10, centrally disposed, into which fluid may be admitted and withdrawn through a pipe 11, and within which is mounted a vertically movable ram 12. The upper

end of the cylinder is packed in the usual manner, as indicated at 13, to prevent the escape of fluid, and the ram 12 carries at its upper end a cross-head 14 of suitable form which may carry rollers 14^a adapted to ride upon vertically mounted col-

umns 16, which may be in the form of commercial I-beams.

The ram 12 supports the loading of the accumulator through connection with the cross-head 14 and in the present instance this loading is sectional in character; that is to say, a part of it is

arranged in what may be termed "units" which are detachably connected to said cross-head.

The columns 16 may be supported by or anchored in a suitable sub-base 17, and the cylinder 10 may be supported by a base section 10^a, mounted upon the sub-base 17. As indicated in the drawings, four columns are provided, and the cross-head is guided in its movement with respect to the same by the rollers 14^a which ride upon said columns. The number of these elements may be altered, as may be desired.

Depending from the cross-head 14 are a series of bolts 20, which are connected at their lower ends to an annular plate or platform 21 which may form the bottom of a cylindrical tank 22 disposed at the upper portion of the accumulator and which, when employed, may be filled with a suitable liquid, or solid material in the form of steel scrap, sand, etc. This tank, when filled or partially filled, may provide any part of the loading of the accumulator, and in some instances may be omitted altogether as hereinafter described. The plate or platform 21, which may form the bottom of this tank, when such structure is employed as a part of the accumulator, is preferably circular and extends outwardly to a point adjacent to the columns 16. This plate or platform carries a series of vertically depending bolts or rods 23; such rods being fixed to said plate or platform 21 and moving with it and hence any movement imparted to the ram will carry said plate or platform 21 and the depending rods 23 therewith.

Between the plate 21 and a series of pedestals 24 or other supports mounted on the sub-base 17, I provide a series of annular plates or platforms, indicated at 25, 25^a and 25^b, and mounted upon the respective plates I arrange a plurality of sets of detachable weights, indicated at 26, 26^a and 26^b. These weights may be segmental in shape and may be arranged to be removable and replaceable, as may be desired, to decrease or augment the load of the accumulator, as hereinafter described.

The several depending rods 23 pass through vertically arranged openings 27 provided in the circular plates or platforms 25, 25^a and 25^b adjacent to the marginal edges of the same, and said rods 23 may be associated or dissociated with these plates or platforms in the following manner. Underlying the rims or margins of each of the plates or platforms 25, et seq., are ring members 28, 28^a and 28^b, respectively; such ring members being supported in place against the underside of the plates or platforms 25, 25^a and 25^b by

means of flanged members 30, which may be secured at spaced intervals to said platforms. The ring members 28, et seq., have limited rotative movement with respect to the plates or platforms 5 25, et seq., and the flanged supporting members 30 carried thereby.

The several depending rods 23 pass through these ring members 28, et seq.; the latter being apertured at 31 for this purpose. The rods 23 10 are provided with a plurality of shouldered portions 23^a underlying the several ring members 28, et seq., carried by the respective plates or platforms 25, et seq., whereby the latter may be supported. The openings 31 in the ring members 15 through which the rods 23 pass are elongated, as clearly shown in Figs. 4, 5 and 6, and are of different dimensions between their end walls so that when said ring members 28, et seq., are in one position with respect to the rods, said ring 20 members are supported by the shouldered portions 23^a of said rods, while when said ring members are in another position with respect to the rods 23, the shouldered portions of the latter may pass through the enlarged portions of the openings 31 in said ring members and through the 25 openings 27 provided in the circular plates 25, 25^a and 25^b adjacent to the marginal edges thereof. This condition is clearly illustrated in Figs. 5 and 6; Fig. 5 showing the narrow portion 31^a of 30 an opening 31 in registry with a rod 23 with the shouldered portion 23^a of the latter underlying the ring member, while Fig. 6 shows the changed position of the ring member, bringing the enlarged portion 31^b of the opening 31 into registry 35 with the shouldered portion of the rod 23; such portion 31^b of said opening being sufficiently large to permit the shouldered portion 23^a of the rod 23 to pass through the same. It will be understood, therefore that when the several ring members, 40 28, et seq., occupy the position indicated by Figs. 4 and 5, they and the superposed circular platforms 25, et seq., will be supported by the shouldered portions of the rods and upon fluid pressure being admitted to the cylinder 10 via the pipe 45 11, the ram will carry up the several annular platforms 25, 25^a and 25^b, suspended from the platform 21, and the several sets of superposed weights 26, 26^a and 26^b.

It may be desirable at times, depending upon 50 the character of work performed by the hydraulic machinery associated with the accumulator, to vary the load and to omit from the loading one or more of the circular platforms 25, 25^a, or 25^b and the superposed weights carried 55 thereby. As may be understood, these platforms must be released from the bottom upward. If therefore it is desired to omit the bottom platform 25^b and the load imposed by its superposed weights 26^b, the bottom ring member 28^b 60 is given sufficient rotative movement to bring the enlarged portions 31^b of the openings 31 of the same into registry with the rods 23 and the shoulders 23^a carried by the same, as indicated by Fig. 6, and upon movement being imparted 65 to the ram the upper part of the structure will be moved and the lower ends of the rods 23 and the shouldered portions thereof will pass through said ring 28^b and through the openings 27 in the margin of the platform 25^b; leaving the latter behind with its superposed weights 26^b. Each plate 70 or platform may be released in a similar manner and, if desired, the entire loading of the accumulator may be reduced to such load as may be provided by the tank 22 and its contents, when employed, or any desired portion thereof.

The provision of a plurality of these annular plates or platforms 25, 25^a and 25^b presents means by which I may, by properly shifting the ring members 28, 28^a and 28^b, add to or subtract from the load which will be lifted by the ram through the medium of the pressure fluid delivered to the cylinder 10, and thereby determine or regulate the pressure delivered from the cylinder 10 of the accumulator when the loaded ram descends. 10

While the ring members 28, et seq., may be moved by any suitable and suitably operated mechanism, or even moved manually, I prefer to move them mechanically, and to provide that such moving means may be under the control of an operator situated at some distance from the accumulator. For this purpose I may provide the mechanism shown generally in Figs. 1 and 4, comprising a series of reversing motors 35, each mounted upon one of the plates or platforms 25, 25^a and 25^b, and operatively connected to suitable reduction gearing diagrammatically indicated at 36; each of said reduction gearing elements driving a shaft 37, carrying a pinion 38, meshing with a rack 39 mounted at an edge portion of the respective ring members 28, 28^a and 28^b. The operation of the motors may be controlled by suitable push buttons disposed at any point remote from the accumulator, and it will be understood that suitable elastic wiring connections capable of permitting such operation will exist between the motors and such push button controls. By such remote control parts of or all of the load suspended from the platform 21 may be subtracted from or added to the ram supporting the 35 head 14 at any time the accumulator structure is in the lowermost position. By having the weights 26, et seq., in segmental sections they may be separately moved as desired to vary the load, when the several plates or platforms 25, et seq., 40 are detached from their operative engagement with the bolts 23.

When it is desired to add the loading afforded by the annular plates or platforms and their superposed weights, the bolts are lowered through the openings 27 adjacent to the margins of said plates and the enlarged portions 31^b of the openings 31 in the ring members, and the latter are again partially rotated so as to bring the parts of said ring members flanking the smaller portions 31^a of the openings 31 therein into the position indicated in Figs. 4 and 5; overlying the shouldered portions of said bolts 23. It will be understood, of course, that the control of the motors will be such as to insure against overrunning so that the positioning of said ring members with respect to the bolts 23, whether to be engaged by the shouldered portions of the latter, or to permit such shouldered portions to pass through the openings in said ring members, 55 will be in proper registry for the respective conditions at each operation of said motors.

The platforms 25, 25^a and 25^b are preferably provided with a series of guide rollers 14^b adapted to ride on the I-beam columns 16 to insure proper alignment during vertical movement of the ram. 65

In some instances, the tank 22 may be omitted altogether, and the space shown as occupied by the same may receive castiron or other metal weights supported by the platform 21 and which may be sectional. In other instances all weighting above the platform 21 may be omitted. 70

Various modifications may be made in the above embodiment of my invention without de- 75

parting from the spirit and scope thereof as set forth in the appended claims.

I claim:

1. An accumulator comprising a cylindrical fluid-containing structure, a ram therein, a cross-head carried on the upper end of said ram, a plurality of weight-carrying sections beneath said cross-head and surrounding the fluid-containing portion of the accumulator, means for releasably connecting said weight-carrying sections to said cross-head including shouldered rods, means comprising revoluble ring members carried by said sections for effecting the connection or disconnection of said weight-carrying members with respect to said shouldered rods, and motor mechanism controllable from a point remote from said accumulator for actuating said ring members.
2. An accumulator comprising a liquid-containing cylinder, a vertically movable ram mounted therein, a cross-head carrying said ram, a plurality of load-carrying platforms encircling said cylinder, means for directly suspending the upper platform from said cross-head, a plurality of shouldered rods depending from the margin of said upper platform; the platforms below the upper platform being supported by said shouldered rods, ring members carried by said lower platforms and resting upon the shouldered portions of said rods; said ring members being revoluble whereby the loaded platforms may be released from the shouldered rods, and motor means carried by said platforms for moving said ring members.
3. The combination with an hydraulic accumulator comprising a liquid-containing cylinder, means for introducing liquid therein and a ram within said cylinder adapted to exert a pressure against the liquid therein, of load supporting means carried by said ram comprising a cross-head connected thereto and held from rotation, a plurality of rods suspended from said cross-head, a platform disposed below said cross-head and supported by said rods, a plurality of shouldered rods hung from said platform, a load-carrying platform below said first-mentioned platform having openings through which said shouldered rods may pass, a ring member carried by said latter platform and having apertures registering with the openings thereof; said ring member being revolubly movable to a position to be supported by the shouldered rods and to a position permitting passage of said rods through the ring and platform, and means carried by said platform for moving said ring to permit or prevent the passage of the shouldered rods therethrough.
4. The combination with an hydraulic accumulator comprising a liquid-containing cylinder, means for introducing liquid therein and a ram within said cylinder adapted to exert a pressure against the liquid therein, of load supporting means carried by said ram comprising a cross-head connected thereto and held against rotation, a plurality of rods suspended from said cross-head, a platform hung from said rods, a plurality of rods hung from the outer margin of said platform; each of said latter rods having a plurality of shoulders, a plurality of load-carrying platforms having openings through which
5. In a structure such as set forth in claim 4, means for moving the ring carried by the load-carrying platform to permit or prevent the passage of the shouldered rods therethrough, comprising a motor carried by said load-carrying platform, gearing actuated by said motor, and a rack carried by said ring and operatively engaged by said gearing.

RICHARD W. DINZL.
